ANTI-SKID UNIT FOR AUTOMOBILE TIRES

Henry L. Bunker, Jr., Swarthmore, Pa., and William J. Powers, Jr., Wilmington, Del., assignors to E. I. du Pont de Nemours and Company, Wilmington, Del., a corporation of Delaware

Filed Oct. 9, 1961, Ser. No. 67,021

Term of patent 14 years

(Cl. D90—20)

FIG. 1

FIG. 2

FIG. 3

FIG. 4

FIGURE 1 is a top plan view of an anti-skid unit for automobile tires showing our new design;

FIGURE 2 is an end elevational view thereof;

FIGURE 3 is a perspective view taken from the left of FIGURE 1;

FIGURE 4 is a fragmentary section taken on line 4-4 of FIGURE 3.

We claim:

The ornamental design for an anti-skid unit for automobile tires, substantially as shown.
